UNITED STATES PATENT OFFICE.

JOHN EDWARD ROTHWELL, OF DENVER, COLORADO.

SEPARATING DEVICE.

1,028,789.

Specification of Letters Patent. Patented June 4, 1912.

Application filed November 16, 1909. Serial No. 528,401.

To all whom it may concern:

Be it known that I, JOHN E. ROTHWELL, citizen of the Dominion of Canada, residing at Denver, Colorado, have invented certain new and useful Improvements in Separating Devices, of which the following is a specification.

My invention relates to a separating device for the separating and washing of liquids from solids, and is particularly adapted for the removal of water from valuable solids preparatory to their after treatment or utility; or, vice versa, the separation of valuable solutions from waste insoluble material, and the washing and extraction of the valuable solutions from the waste material and the automatic delivery of the said solutions and solids to receptacles prepared to receive the same, prior to their further after treatment, or storage.

The object of my invention is to furnish a device, simple in construction and operation, and of minimum cost, to accomplish the results sought in a practical and economical manner.

In the accompanying drawings, Figure 1 is a plan view showing twelve trays, one being shown as tilted. Fig. 2 is a sectional elevation of the machine. Fig. 3 is a longitudinal sectional elevation of the separating trays and accompanying mechanism. Fig. 4 is a cross section in elevation of the same. Fig. 5 is a plan view of the same. Fig. 6 is a plan view of a detail. Fig. 7 is a cross section in elevation of the same. Fig. 8 is a detail view. Fig. 9 is a plan view of a detail. Fig. 10 is an elevation and section of a detail. Fig. 11 is a detail.

In Figs. 1 and 2, 1 is one of a series of twelve separating trays, in all of which, in rotation, the mixture of solids and liquids, which I will call hereinafter the pulp, is distributed from a stationary distributing launder shown at 2. I do not limit myself to any fixed number of trays, as this feature is only determined by the size of the machine required for any certain purpose, the number being made to suit the size of tray required for convenient handling.

The trays are made up of any suitable materials, the illustrations Figs. 3, 4 and 5 showing a tray with a wooden bottom *a*, and metal sides and ends *b* and *c*. The sides of the tray conform to a radial line dependent on the number of trays used for a given size of machine, so that when the trays are

placed side by side they will conform to a continuous annular or polygonal shaped horizontal plane. The sides of the trays are slightly flaring outwardly, and at the top edge a flexible packing strip *d* is attached for the purpose of maintaining a water tight joint between each tray when they are in a horizontal position.

The inside bottom of the tray is provided with a suitable opening *e*, for the outflow of the separated liquid, and from this opening tapering grooves *f* radiate, which conduct the separated liquid to the outflow opening. A porous diaphragm made up of metal screen cloth, burlap and canvas is laid and held in place by the metal sides *b* and *c*, and is further bound with taut wires *h*, placed on radial lines, as shown in Figs. 1 and 5.

The trays are fastened to trunnion castings —3— Figs. 3 and 4, with bolts. These trunnions have openings *3^a*, *3^b*, forming conduits to and from the trays for purposes hereinafter described; a rubber gasket or other suitable ring *3^d* forms a water tight joint between the tray and trunnion, and the opening *e* in the tray and conduit *3^a* in the trunnion casting coincide. Attached to or a part of the trunnion casting is a crank arm 3 as shown in Figs. 2 and 3.

The trunnion casting is supported in bearings 4 and 5, which are in turn a part of or attached to the frame work 6, and this frame is fastened to the track ring 7. This track ring is supported on suitable rollers 8, and the whole rotated by gearings, as 9, *9^a* and *9^b*, which shows a suitable method of traction drive, although any other method of toothed gearing may be employed.

The crank arm *3^e* has a connecting rod 10, with a pin *10^a* and roller *10^b*, working in a curved or cam track 30 to actuate or tilt the tray at the proper time.

Attached to the trunnion box are packing glands 11—12, forming a water tight connection around the stationary pipes 13—14 which form the connecting conduits between the separating trays and the central disk 15.

A pipe *14^a*, Fig. 3, is threaded into the conduit *3^b* and terminates in the header *14^b*. This header is perforated at *14^c* for the outlet of air or liquid under pressure.

The pipes 13—14 are connected with the disk 15, as shown in Fig. 8. The disk is drilled with two rows of concentric holes *13^a* and *14^a*, and these holes are extended radially to the periphery of the disk and

threaded for connection with the pipes 13 and 14. These pipes also act as spokes and rotate the disk with the frame carrying the separating trays, at the same time forming a conduit from the separating trays to the stationary disk 16.

The stationary disk 16 is known in plan and section Figs. 9 and 10, has two depressions 16^a and 16^b with outlets for pipe connections 16^c and 16^d, in turn connected with vacuum pumps or receptacles in which a vacuum is maintained. These grooves, when the disk 16 is placed against the disk 15, as in Fig. 10, coincide with the line of holes 13^a, Fig. 8. In the disk 16 are also located two holes 16^e and 16^f Fig. 8 with their respective pipes, Fig. 10, which in turn are connected with a source of pressure of either liquid or air, or both, as found necessary. The opening 16^e is in the same circle as the grooves 16^a and 16^b, and when in connection with disk 15, coincides with the holes 13^a. The hole 16^f is in a concentric circle to 16^e and coincides with the openings 14^d of disks 15, as shown in Fig. 10.

The two disks 15 and 16 are supported on the standard 17 and base 18 Fig. 10, and are held in an air and water tight connection by the spiral spring 19, which is held 30 in compression by the split nut 20. This nut is inserted in the crank arm 21, which, when rigidly fastened, holds the disk 16 stationary by the pin 22 at any desired position in the horizontal plane as required. 35 The curved track shown in Figs. 6 and 7 is placed as shown in Figs. 1 and 2, and its function is to actuate the roller 10^b, attached through its connecting rod with the trunnion casting of each separating tray, 40 and turn the tray from its horizontal position upwardly and outwardly to a vertical position, for the purpose of discharging the solids that have been retained on the porous diaphragm of the separating tray.

45 In operation and for illustration I will describe the treatment of gold and silver ores by the cyanid process. The pulp, after the necessary preliminary treatment by which the metal values have been dissolved, 50 is distributed by the stationary distributing box 2 evenly on to the separating diaphragm in the tray that is passing slowly below it. When this tray has passed beyond the line of the distributor, it is loaded to the desired 55 depth, this being determined by the amount of inflow and speed of rotation. It is then in a condition to be separated and washed. This action begins when the opening 13^a Fig. 8, in its rotation coincides with the 60 grooved depression 16^a of the stationary disk 16, Fig. 9, in which a vacuum is maintained through the pipe 16^c, by a vacuum pump, the location of which is adjacent to the machine but not necessary to show. The 65 solution is thereby drawn away from the

finely divided solids, which remain in the tray on the porous diaphragm. This draining action continues during the rotation as long as the opening 13^a coincides with the groove. At some point in the revolution of the tray, such as at X and Y, Fig. 1, a wash solution and wash water is sprayed or flooded into the tray and is drawn through as long as the opening 13^a coincides with the grooves 16^a and 16^b. The 70 partition shown between the ends of these grooves is for the purpose of separating the strong or more valuable solution from the weak or less valuable solution. By the time 75 tray has moved around to the position shown by the tilted tray, Figs. 1 and 2, the liquids have been eliminated sufficiently from the solids, and these solids are then in a condition to be discharged from the trays and the tray made ready for its loading again with 80 pulp. 85

The discharging of the tray is accomplished by the tilting action already described, so that when in a vertical position the opening 13^a coincides with the opening 90 16^e water or air pressure is admitted from some outside source, not shown, connected with the pipe 16^c, and passing through the pipe 13^a to the under side of the porous diaphragm frees the solids from same, and 95 at the same time the opening 14^d coincides with the opening 16^f through which a pressure of water or air is admitted to the pipe 14 of the tilted tray and conduit 3^b in the trunnion casting to the pipe 14^a and perforated header 14^b, thus blowing the solids 100 off the porous diaphragm and into the receptacle Z, in which they are removed to any desired point as required, but not necessary to show. The tray in its further rotation is again brought to a horizontal position and is ready to receive a new charge of the pulp. 105

Each tray of the series follows the cycle of operations described.

I claim:—

1. A separating device comprising a series of trays placed side by side, means for moving the trays, and packing strips located between the trays.

2. A separating device comprising a series of trays, means for rotating the same, filter means in said trays, central suction means, a pipe leading from said means to each tray for drawing the solution therefrom as the 120 tray moves, means for tilting the tray at a certain point, and means for cutting the suction off when the tray is tilted and forcing fluid through the said pipe to the tray below the filter, and independent means for conducting compressed fluid against the material on the top of the filter means.

3. A separating device comprising a rotary disk and a stationary disk, trays surrounding said disks, a suction pipe and a 130

pressure pipe connecting each tray with the rotary disk, said rotary disk having a ring of suction openings therein communicating with the suction pipes and another ring of 5 pressure openings communicating with the pressure pipes, said stationary disk having grooves in its inner face adapted to communicate with the suction openings, and also having openings adapted to communicate 10 with the pressure openings, pressure and vacuum means connected with said grooves, and openings in the stationary disk and spring means for holding the disks together.

15 4. A separating device comprising a stationary disk and a movable disk having grooves and ports therein, a shaft supporting said disks, a spring coiled around the shaft and pressing the stationary disk 20 against the movable disk, a split nut on said shaft engaging the other end of the spring, a sleeve surrounding the nut, an arm on said sleeve, a rod on the stationary disk engaging the arm, trays surrounding the 25 disks, means for rotating the trays and pipes connecting the trays with the ports in the movable disks.

5. A separating device comprising a series of trays, means for rotating the same, trun-

nions arranged at right angles to the radial line for supporting the trays, means for tilting the trays on said trunnions at a certain place, and means passing through the trunnions for withdrawing the solution from the trays or applying fluid thereto. 30 35

6. A separating device comprising a series of trays, means for rotating the same, hollow trunnions arranged at right angles to the radial line for supporting the trays, means for tilting the trays on the trunnions 40 at a certain place, means passing through the trunnions for withdrawing the solution from the trays or applying fluid thereto, and removable means for attaching said trays air tight to the trunnions. 45

7. In filtering apparatus of the class described, a rotatable frame, a filter mounted on said frame, and a washing device mounted on said frame in fixed relation to and suitably spaced from said filter, substantially as described. 50

In testimony whereof, I affix my signature in presence of two witnesses.

JOHN EDWARD ROTHWELL.
